DESIGN FOR A SUITCASE SEAT

Patrick J. Gormley, Frankfort, Ky.

Application January 22, 1946, Serial No. 125,843

Term of patent 14 years

(Cl. D87—5)

To all whom it may concern:

Be it known that I, Patrick J. Gormley, a citizen of the United States, residing at Frankfort, in the county of Franklin and State of Kentucky, have invented a new, original, and ornamental Design for a Suitcase Seat, of which the following is a specification, reference being had to the accompanying drawing, forming a part thereof.

Figure 1 is a perspective view of a suitcase seat showing my new design.

Figure 2 is a top plan view of the suitcase seat.

I claim:

The ornamental design for a suitcase seat, as shown.

PATRICK J. GORMLEY.
